UNITED STATES PATENT OFFICE.

ROSCOE S. E. TURNER, OF PHILADELPHIA, PENNSYLVANIA, ASSIGNOR TO MORRIS H. STARR, OF PHILADELPHIA, PENNSYLVANIA.

TOOL-OPERATING MACHINE.

1,324,136.

Specification of Letters Patent.

Patented Dec. 9, 1919.

Application filed March 28, 1917, Serial No. 157,871. Renewed May 5, 1919. Serial No. 295,032.

To all whom it may concern:

Be it known that I, ROSCOE S. E. TURNER, a citizen of the United States, residing at Philadelphia, in the county of Philadelphia and State of Pennsylvania, have invented certain new and useful Improvements in Tool-Operating Machines, of which the following is a specification.

One object of my invention is to provide a machine of the above type which will be of simple construction and which can be easily manipulated.

Another object is to provide my improved machine with means whereby the tool can be quickly and easily raised and lowered without changing the position of the work table.

A further object is to so make my invention that the table can be quickly and easily turned and secured at various angles.

A still further object is to so construct my improved machine that it can be used for heavy practical work and can also be used with great advantage in manual training schools or the like.

These objects, and other advantageous ends which will be described hereinafter, I attain in the following manner, reference being had to the accompanying drawings in which—

Figure 1 is a front elevation of my improved machine.

Fig. 2 is a top plan view of Fig. 1 with the work table removed.

Fig. 3 is a sectional elevation taken on the line 3—3 of Fig. 1.

Fig. 4 is a top plan view on a reduced scale showing the work table.

Fig. 5 is a detached perspective view showing certain of the elements of my invention.

Fig. 6 is a front elevation showing a slightly modified form of my invention.

Fig. 7 is a side elevation of Fig. 6, and

Fig. 8 is a sectional elevation on the line 8—8 of Fig. 6.

Referring to Figs. 1 to 5 inclusive, 1 represents a standard which can be secured to the floor and is shown broken away in Figs. 1 and 3. This standard forms the support for a base 2, the latter being secured in the present instance by bolts 3^a to the standard 1. This base 2 has a recess 3, preferably

located centrally between the side surfaces thereof, and this recess 3 extends vertically 55 and intersects the upper surface 4 of the base (see Figs. 1, 2 and 5).

Furthermore, this recess has its opposite surfaces 5 arranged parallel to form a slide-way for the saw-carrying bearing. This 60 bearing comprises a block 6 which has opposite plane surfaces 7, designed to slidably fit against the surfaces 5 of the slideway, and a flange 8 which is designed to embrace the rear face of the base 2.

An extension 9 is provided on said block, and this extension forms the lower half of the journal for carrying a shaft 10 which supports the circular saw 11. A bearing cap 12 forms the upper half of the journal bearing and is secured to the extension 9 by bolts 13.

A plate 14 has two opposite faces 15 which register with the faces 7 of the block 6 and also slide within the slideway provided by 75 the recess 3. A stud 16 has one end rigidly secured within the plate, and the other end designed to freely pass through a hole 17 in the block 6. This latter mentioned end of the stud 16 is provided with screw-threads 80 and is of such length as to project beyond the rear surface of the block 6 (see Fig. 3).

A handle 18 has a threaded opening which is designed to engage the threaded end of the stud 16 and bear against the rear face of the 85 block 6 so that a rotation of said handle in one direction will serve to move the plate 14 and block 6 toward each other and to bind the flange 8 of the block 6 against the rear face of the base 2 and will also serve to bind 90 a flange 19 of the plate 14 against the forward face of the base 2, thus firmly securing the block and plate to the base.

The upper end of the plate 14 has a pin 20 designed to enter a cavity 21 in a forward 95 overhung portion 22 of the extension 9 (see Figs. 3 and 5). The block 6 has an internally screw-threaded hole 23 which is arranged vertically and is designed to receive the upper threaded end of a vertical post 24, 100 the latter being rotatably mounted and seated within the lower end of the recess 3 (see Figs. 1, 3, and 5).

The post 24 has a beveled gear 25 secured thereto and meshes with another beveled 105 gear 26 secured to the inner end of a manu-

ally operative shaft 27, the latter being journaled within the base 2 in such position that the gear 26 is arranged above the gear 25 and thereby prevents the post 24 from moving vertically.

- The shaft 27 at its outer end, is provided with a crank arm 28 and handle 29, whereby the post 24 can be rotated through the medium of said gears and shaft 27. The shaft 10 has a collar 30 which is rigidly secured thereto and forms the abutment for one face of the saw 11 and a nut 31 screwed onto the threaded end 32 of the shaft 10, serves to securely bind the saw to the collar 30.
- 15 The opposite end of the shaft has a driving pulley 33 secured thereto which is rotatable by a belt 34. This belt has its upper run 35 engaged by a take-up roller or pulley 36, the latter being rotatable on an arm 37 which is pivotally mounted on a bracket 38 secured to the base 2 by a bolt 39. The arm 37 is acted upon by a coiled spring 40 which, in the present instance, is connected with the standard 1. The function of this roller 25 36 is to take up slack which occurs due to vertical adjustment of the saw - carrying shaft 10 as will hereinafter be more fully explained.

The base 2, adjacent to its upper portion, 30 has two extensions 41 and 42. These extensions at their lower ends are provided with bosses 43 and 44 respectively. These bosses are provided with threaded openings 45, either of which can be engaged by a threaded rod 46 which is secured to a hand lever 47 and is designed to protect through a segmental slot 48 in depending portions 49 of supporting arms 50 for the work table 51. These arms 50 have holes 52 therein designed to be engaged by pivot pins 53 which 35 are secured within the upper portions of the extensions 41 and 42, the axes of these pivot pins 53 being in a different vertical plane from the axes of the threaded openings 45 above referred to, thus permitting the table 51 to tilt or turn on the pivot pins 53 without greatly changing the relative position, with respect to the saw, of an opening 54 in a block 55 through which the saw 40 extends (see Fig. 3).

This block 55 is readily removable from the table proper and rests upon ledges 56 formed within said table top so that the top of the block 55 is substantially flush with the top 55 of the table 51.

In operation, when it is desired to change the position of the saw with respect to the top of the work table 51, the handle 18 is loosened to relieve the binding action between the plate 14 and the block 6. The shaft 27 is then rotated through the medium of the handle 29, and since the post 24 cannot move vertically, the effect of the screw-threads on the post and the internal screw-

threads within the block 6 will cause the latter to move vertically in a direction dependent upon the direction of rotation of said shaft 27.

After the proper height of the saw has been attained, the handle 18 can be turned to again clamp the block 6 and plate 14 to the base 2 and the machine is ready for operation.

It will be noted that according to the arrangement of the belt illustrated, if the saw 75 is lowered, the spring 40 will serve to pull the take-up roller downwardly and thereby take up any slack in the run 35 of the belt. On the other hand, if the saw is moved upwardly, the spring 40 will yield in proportion to the upward movement and thereby prevent undue strain on the belt.

When it is desired to tilt the table, the hand lever 47 can be readily loosened and after the table top has been rocked on the pivot pins 53, the hand lever 47 can be again tightened to secure the table in the adjusted position.

I preferably provide fingers 57 at the extreme top of the base 2 which act as additional supports for the table when the latter is in a horizontal position and which also act as stops to permit the return of the table to a horizontal position.

I provide a rail 55^a on the top of the work 95 table 51 and provide this rail with two longitudinally slotted arms 56^a. Clamping bolts 57^a are designed to extend through the table 51 and through the slots within the arms 56^a so that the rail 55 may be moved 100 toward or from the saw 11.

In Figs. 6 to 8 inclusive, I have shown a form of my invention which can be made extremely small and is well adapted for household use, manual training schools, or other places where a serviceable little machine is desired. In this form of my invention, I eliminate the means for raising and lowering the circular saw such for example as the elements including the post 24, 110 gears 25, 26, and handle 29.

Referring to Figs. 6, 7, and 8, 58 represents a base which provides a vertical slide way 59 for a block 60, and a plate 61, said block and plate being provided with flanges 115 62 and 63 which respectively embrace opposite faces of the base 58. The plate 61 has a stud 64 of similar construction to the stud 16 above described, and said stud 64 extends through the block 60 and at its outer threaded end is provided with a wing nut 65 which serves to bind the plate 61 and block 60 to the base 58.

The block 60 has an extension 66 which forms a bearing for a shaft 67, said shaft having a collar 68 thereon against which abuts a circular saw 69. A nut 70 is mounted on the threaded end 71 of the shaft 67

and is designed to clamp the saw against the collar 68. The opposite end of the shaft 67 is provided with a pulley 72. A work table 73 has arms 74 which are designed to rock 5 upon pivot pins 75 which project from opposite extensions 76 and 77 of the base 58.

A threaded stud 79 is mounted in the extension 77 and has a wing nut 80 thereon which is designed to frictionally engage a 10 depending portion 81 of one of the supporting arms 74. Fingers 82 extend from the forward face of the base 58 and form limiting means for the work table 73. The table 73 is provided with an opening 83 through 15 which the saw 69 extends as shown in Fig. 8.

A guiding rail 84 is designed to slide on the upper face of the work table 73 toward and from the saw 69. This rail has bolts 85 which extend therethrough and which 20 ride within slots 86 formed within said table adjacent opposite ends thereof.

The rail 84 acts as a guide for the edge of the material to be sawed. I preferably insert a screw 87 through the plate 61 and block 60, and while this screw forms a loose 25 connection between the block 60 and the plate 61, it serves to prevent undesirable jamming between said plate and block, so that when the wing nut 65 is turned, the 30 plate 61 and block 60 will move smoothly toward or from each other.

In this form of my invention, the saw 69 can be adjusted vertically by hand after the wing nut 65 has been loosened, and the 35 table 73 can be turned on the pivot pins 75 by loosening the wing nut 80 and can be secured in a tilted position by tightening on said wing nut 80.

While I have described my invention as 40 taking a particular form, it will be understood that the various parts of my invention may be changed without departing from the spirit thereof, and hence I do not limit myself to the precise construction set 45 forth, but consider that I am at liberty to make such changes and alterations as fairly come within the scope of the appended claims.

Having thus described my invention, what 50 I claim as new and desire to secure by Letters Patent is:

1. A machine of the character described including a base having a recess providing a slideway; a block having a portion slidably 55 fitting said slideway and a flange for engaging one outer side surface of the base adjacent the slideway; a plate adapted to engage the opposite side surface of the base; a bearing on said block; an actuating shaft 60 mounted within said bearing; and clamping means for moving said plate and block together to clamp them to opposite side surfaces of the base and to secure them to each other, substantially as described.

2. A machine of the character described 65 including a base having a recess providing a slideway; a bearing having a portion slidable within said slideway and a flange for embracing one side surface of the base adjacent said slideway; a plate adapted to 70 embrace the opposite side surface of said base; an actuating shaft in said bearing; and clamping means carried jointly by said bearing and plate for moving said plate and flange of said first portion into engagement 75 with said opposite side surfaces of the base to clamp the bearing and the plate to the base, substantially as described.

3. A machine of the character described 80 including a base having a recess providing a slideway; a block having a portion slidably fitting said slideway and a flange for engaging one outer side surface of the base adjacent the slideway; a plate having a flange adapted to engage the opposite side 85 surface of the base and a portion slidably fitting said slideway and bearing on said block; an actuating shaft mounted within said bearing; and clamping means for moving said plate and block together and clamping 90 said flanges against the opposite side surfaces of the base and to secure the plate and block together, substantially as described.

4. A machine of the character described 95 including a base having a recess providing a slideway; a block having a portion slidably fitting said slideway and a portion for engaging one side surface of the base adjacent the slideway; a plate adapted to embrace the opposite side surface of the base; a stud on the plate having a threaded outer end, said block having a hole through which 100 said stud extends; a clamping member having a threaded opening designed to operatively engage the screw threaded end of the stud and adapted to bear against the block, said block having a portion providing a bearing; and an actuating shaft within 105 said bearing, substantially as described.

5. A machine of the character described 110 including a base having a recess providing a slideway; a block having a portion slidably fitting the slideway and a portion for engaging one side surface of the base adjacent the slideway; a block adapted to embrace the opposite side surface of the base; a plate; a stud therein; said block having a hole through which said stud extends; means for clamping said plate and block 115 to the opposite side surfaces of the base, said block having a portion providing a bearing, said bearing having a cavity; and a pin fitting said cavity and attached to said plate, substantially as described.

6. A machine of the character described 120 including a base having an elongated recess extending downwardly from the top thereof

4
and entirely through the width thereof, said recess providing a slideway; a bearing movable within the slideway; an actuating shaft within the bearing; and means movable in conjunction with the bearing for adjustably clamping the bearing to the base, substantially as described.

In testimony whereof I have signed my name to this specification in the presence of two subscribing witnesses.
